UNITED STATES PATENT OFFICE.

THOMAS H. HANRATTY, OF BUTLER, PENNSYLVANIA.

DESIGN FOR A PLATE, PLAQUE, PLATTER, OR SAUCER.

53,244.

Specification for Design.

Patented Apr. 29, 1919.

Application filed July 15, 1918. Serial No. 245,115. Term of patent 7 years.

To all whom it may concern:

Be it known that I, THOMAS H. HANRATTY, a citizen of the United States, and residing at Butler, in the county of Butler and State of Pennsylvania, have invented a certain new, original, and ornamental Design for a Plate, Plaque, Platter, or Saucer, of which the following is a specification, reference being had to the accompanying drawing, forming a part thereof, which is a face view in elevation of a plate, plaque, platter, or saucer illustrating my new design.

The back ground of the article is white, portion 2 red, portions 3 and 4 khaki color and the star 5, navy blue. Line 6 is khaki color and line 7, blue.

I claim:

The ornamental design for a plate, plaque, platter, or saucer, substantially as shown.

THOMAS H. HANRATTY.
